CLAIM

The ornamental design for a remote training collar device, as shown and described.

DESCRIPTION

FIG. 1 is a perspective view of a remote training collar device showing my new design;

FIG. 2 is a top view thereof;

FIG. 3 is a bottom view thereof;

FIG. 4 is a right-side view thereof;

FIG. 5 is a left-side view thereof;

FIG. 6 is a front view thereof; and,

FIG. 7 is a back view thereof.

The broken lines in the drawings depict portions of the remote training collar device that form no part of the claimed design.
